BOOKKEEPING MACHINE

Bruno Bornkessel, deceased, late of Essen-on-the-Ruhr, Germany, by Martha Bornkessel, administratrix, Essen-on-the-Ruhr, Germany, Ernst Breitling, Wilhelm Brauer, and Karl August Lehmann, Essen, Germany, assignors, by mesne assignments, to The National Cash Register Co., Dayton, Ohio, a corporation of Maryland

Original application February 24, 1925, Serial No. 11,373, Patent No. 1,896,936, dated February 7, 1933. Divided and this application October 25, 1927, Serial No. 228,679. In Great Britain January 19, 1925.

20 Claims.

The invention relates to a mechanism to be combined with the printing mechanism of cash registers and calculating machines and intended to control the coupling of the different sub-mechanisms of said printing mechanism with the actuating means. While in the known devices of this type the setting means of the machine are in direct connection with the several sub-mechanisms of the printing mechanism by different members which are independent of one another, the setting means of the machine are connected, according to the invention, with a common controlling mechanism of the printing mechanism, said setting means regulating the adjustment of this common controlling mechanism, which is adapted to act upon all the coupling means inserted between the actuating means and said sub-mechanisms of the printing mechanism. This arrangement affords the advantage that the mutual relations of the individual sub-mechanisms may be regulated as desired by a simple construction.

Further characteristic features of the invention have reference to the design of the individual sub-mechanisms of the printing mechanism, and to their mutual co-operation, to perform the particular functions desired in bookkeeping machines.

With these and incidental objects in view, the invention consists in certain novel features of construction and combinations of parts, the essential elements of which are set forth in the appended claims, and a preferred form of embodiment of which is hereinafter described with reference to the drawings which accompany and form part of this specification.

In these drawings:

Fig. 1 is a front view of the machine,

Fig. 2 is a section through the machine on line II-II of Fig. 1,

Fig. 3 is a top view of the means controlling the adding mechanisms and of the means connecting them with the printing mechanism,

Fig. 4 is a section on line IV-IV of Fig. 1,

Fig. 5 is a top view showing the arrangement of the type wheels of the printing mechanism and the actuating mechanism for the account numbers,

Fig. 6 is a top view of the control mechanism for the printing mechanism and of the means actuating the sub-mechanisms of the latter,

Fig. 7 is a top view of the control strip feeding mechanism,

Fig. 8 is an elevation showing the connection

(Cl. 235-7)

of the drive of the printing mechanism with the main actuating shaft of the machine,

Fig. 9 is an elevation showing the control strip feeding mechanism and the feeding mechanism for the book and the card,

Figs. 10 and 11 are elevations, partly in section, showing the members connecting the type wheels and the respective members of the differential mechanism,

Fig. 12 is an elevation of the means actuating the control mechanism for the printing mechanism,

Figs. 13 to 20 are elevations, partly in section, of the actuating and controlling means for the different sub-mechanisms of the printing mechanism,

Fig. 21 shows a printed card,

Fig. 22 shows a printed page of the book,

Figs. 23 and 24 show two kinds of receipts,

Fig. 25 shows the printed control strip, while

Figs. 26 and 27 are elevations of mechanisms intended to control the sign to be printed with the amounts to be recorded,

Fig. 28 is a detail view of the plus and minus sign printing wheel.

Fig. 29 is a view partly in plan and partly in horizontal section of the auxiliary totalizer,

Fig. 30 is a vertical transverse section of the auxiliary and main totalizers,

Fig. 31 is a rear elevation of the throw-in and adjusting mechanism for the main totalizer and the transaction totalizer,

Fig. 32 is a vertical section on the line 32-32 of Fig. 4,

Fig. 33 is a fragmentary plan view partly in section of the account number adjusting mechanism.

The invention relates more particularly to matter divided from our co-pending application Serial Number 11,373, filed February 24, 1925, for a bookkeeping machine. This application was issued on February 7, 1933 as United States Patent No. 1,896,936. The machine is designed to calculate and record the money transactions between an unlimited number of customers and a banking house. Each customer is assigned an account number, by which the transactions in his account are identified. For recording the transactions and the state of account a card and a book are used, the card remaining in the bank and the book being retained by the customer. The book must be presented in the bank for recording the amounts in consideration. In case this is impossible the record is made thereon at a later date.

For controlling the transactions there is also a control strip on which certain of the operations are recorded. The machine also issues a receipt showing all the operations involved in a particular transaction. There is also provided a display mechanism which may be read from both the front and rear of the machine.

One of the totalizers of the machine, the main-totalizer, is used for calculating a new state of account consisting of an old state and of the amounts received or paid out. Another totalizer, i. e. the auxiliary totalizer, is used to calculate the algebraic total of the amounts received and paid out in the different accounts over a particular period. Other totalizers, i. e. the transaction totalizers, are used in connection with the individual operations of the main totalizer. The control of the machine is exercised entirely by keys, some of which cause a plurality of operations to be executed simultaneously. These keys are connected by suitable interlocks to properly control the depression thereof. These interlocks make it necessary to complete a keyboard setting so that a transaction cannot be only partially recorded. A certain number of the keys are connected, for control purposes, with item counters. Each transaction to be executed by the machine, total-making including, requires an operation of the machine initiated by depressing a motor key.

The machine is driven by an electric motor.

General arrangement of the machine

The setting mechanism of the machine (Fig. 1) consists of amount keys 10, arranged in nine rows at the left-hand side of the machine, two rows of special keys 11 and 12, three rows of account totalizer keys 13 and a motor key 14 at the right-hand side of the machine. To the keys 13 are allotted the item totalizers 15 and to the six upper keys of key row 11 are allotted the item totalizers 16. The lower front part of the machine is occupied by the printing mechanism arranged across the machine (Figs. 1 and 4), said mechanism showing, at its upper side, seven rows of keys 17 serving for setting the account number wheels. The key 18 is a general releasing key for the keys 17. In the upper part of the machine is arranged the display mechanism which may be read from both the front and rear of the machine.

The left-hand part of the interior of the machine is occupied by the amount differential mechanism and the totalizers (Fig. 2). The totalizers are arranged as follows: twenty-seven account totalizers forming three groups N₁, N₂, N₃ of nine totalizers each (Fig. 2); six transaction totalizers forming a group S; an auxiliary totalizer HR arranged below the group S; and a main totalizer R. The main and auxiliary totalizer are designed for addition and subtraction while the other totalizers are adapted to be used for addition only. As will be seen from Fig. 2, each two groups of totalizers are supported on three blocks 19, 20, 21, the latter being fixed on parts of the frame 23 by means of machine screws 22.

The right-hand part of the interior of the machine is occupied by the controlling devices for the totalizers, the interlocks for the keys, and the driving mechanism.

The kinds of record

Four different kinds of record are capable of being executed by the machine:

75 I. The ordinary record (record of first order);

II. Recording the sub-total from the main totalizer (record of second order);

III. Recording sub-totals and grand-totals from the controlling totalizers (record of third order);

IV. Recording addenda (record of fourth order).

I. An ordinary record requires three different types of operations viz: introduction of the old state of account, introduction of the amounts received or paid out, recording of the new state of account.

The operation of the main totalizer and the simultaneous throwing in of a controlling totalizer of the group S (Fig. 2) are controlled by the six upper keys -B, +B, Ab, Zu, -b, +b (Fig. 1) of row 11, said keys being termed hereinafter the main keys. The keys -B and +B set the machine, respectively, for setting up a negative old balance and a positive old balance; the keys Ab and Zu set the machine, respectively, for entering amounts paid out and amounts paid in; the keys -b and +b set the machine, respectively, for drawing a negative new balance and a positive new balance. The key RZ sets the machine for taking a sub-total from the main totalizer and the key HR sets the machine for throwing in the auxiliary totalizer, although a special control described later prevents the auxiliary totalizer from being thrown in except when the machine is set for amounts received or paid out, or for drawing a total from the auxiliary totalizer. The by-keys 13 can be depressed only upon introducing amounts received and paid out. When this takes place they cause an account totalizer to be thrown in, to which the amount received or paid out is transmitted additively. The account totalizers are subdivided into two groups, the group controlled by the by-keys 1 to 9 and 19 to 23 being allotted to the amounts received and the group controlled by the by-keys 10 to 18 and 24 to 27 to the amounts paid out.

In order to introduce the old state in the machine, after depressing the corresponding amount keys 10 and account keys 17, one of the keys -B and +B is depressed, the key +B if the amount is positive, and the key -B if it is negative. The motor key M, which is normally locked against depression, is then released and the operation of the machine is started, the set amount being transmitted to the main totalizer, the corresponding transaction totalizer -B or +B, and to the printing and display mechanism. A transmission of the set amount to the auxiliary totalizer does not take place even in case the key HR is depressed.

In order to introduce amounts received or paid out, after setting up the proper amount on the keys 10, the by-key 13 is depressed, and the motor key M is released by depressing one of the main keys Zu or Ab. During the operation of the machine the amount is transmitted additively or subtractively to the main totalizer and additively to the transaction totalizer Zu or Ab, to the account totalizer thrown into operation and to the printing and display mechanism. If the key HR is depressed, the amount is transmitted additively or subtractively to the auxiliary totalizer. This operation may be followed by any number of operations for entering amounts received or paid out.

The third mode of operation takes the total from the main totalizer. One of the main keys -b, +b is locked depending upon whether the main totalizer is in a positive or negative condi-

tion. There is also provided means to cause one of the keys $-b$, $+b$ to be unlocked for depression only if no amount key is depressed. By depressing one of the keys $-b$, $+b$ the motor key M is released. During the operation now following the main totalizer is zeroized and the total contained therein is transmitted additively to the corresponding transaction totalizer $-b$ or $+b$, and the printing and display mechanism is operated. A transmission to the auxiliary totalizer does not take place even in case the key HR is depressed.

The keys ZS and ES set the machine for taking, respectively, sub-totals or grand totals from the transaction totalizers S, the auxiliary totalizer HR, or the account totalizers N₁, N₂, N₃.

While the amount keys 10, the main keys, the key RZ and the keys ZS, ES are released at the end of each operation of the machine, the keys 20 HR (auxiliary totalizer) and N (addenda) remain permanently depressed. They are released only by the keys L disposed below and above them, respectively. The account keys 11, set at the beginning of an ordinary transaction, are 25 released only at the end thereof, viz. after the new state of account has been printed.

II. As the main totalizer is zeroized at the end of any ordinary transaction, a sub-total can be 30 taken therefrom only after an amount received or paid out has been entered. By depressing the key RZ (sub-total of the main totalizer) the motor key M is released, such depressing being possible only if no amount keys are depressed. Upon starting the machine, the transmission of the sub- 35 total from the main totalizer to the printing and display mechanism takes place. In case this sub-total is negative, the machine automatically adjusts itself in the manner described for taking negative totals.

40 III. If from one of the six transaction totalizers $-B$, $+B$, Ab, Zu, $-b$, $+b$, from the auxiliary totalizer, or from one of the account totalizers, the total is to be taken, one of the keys ZS (sub-totals) or ES (grand totals) is first depressed, 45 this being possible only if none of the amount keys are depressed. By depressing the keys ES and ZS, the keys HR and the by-keys 13, which generally do not cause the release of the motor key M, become release keys for the motor key. 50 If one of the main keys is now depressed, or one of the by-keys, or the key HR, the motor key M is released and the sub-total or grand total is taken from the totalizer selected.

IV. The key N is depressed in case a transaction is to be recorded as addenda. With the addendum key N depressed, all the totalizers are thrown out of operation except the main totalizer. The calculation of an ordinary transaction by the main totalizer is therefore effected by 60 depression of this key, although the totalizers allotted to the by-keys are not, even though they are depressed for this operation.

The depression of the addendum key N besides causes certain special operations to be effected, 65 as hereinafter described. As to the rest, the mode of function of the machine is the same as in an ordinary transaction.

Amount differential mechanism

70 Amounts are inserted in the totalizers and totals taken therefrom by means of a differential mechanism shown principally in Fig. 2, which also serves to adjust the display wheels and printing mechanism. In the differential mechanism are differential members 80, 65 pivoted to-

gether by a pin 83. The member 65 is provided with a series of lugs 89-96, each adapted to cooperate with one of the keys 10. The differential member is moved downward at each operation and in entering amounts is stopped in a position determined by the abutment of one of the lugs 89-96 against the key 10 which has been set. There is one differential member for each vertical row of keys 10. The bar 80 is provided on its rear edge with a series of rack teeth 85 10 which engage a series of intermediate pinions 164 rigidly connected to intermediate wheels 165 in mesh with differential wheels 154 of the account and transaction totalizers, and differential wheels 214 of the auxiliary totalizer (Fig. 29) and 214 15 of the main totalizer. The differential wheels are connected to the totalizer wheels in a manner which will be explained later.

For moving the rack bars 80 down at each operation of the machine, there is provided beside the rack bar 80 (behind the rack bar in Fig. 2) a driving member provided with a series of teeth 71. The body of the driving member, which is a bar similar to 80, is covered in Fig. 2, but the corresponding bar 76' of the totalizer 25 control differential mechanism, which is substantially the same as the amount differential mechanism is shown in cross section in Fig. 3 at 76'. Behind the driving member is another 30 bar, the coupling member 81, a projecting shoulder of which appears in Fig. 2. The coupling member is connected to the bar 80 by a spring 99 which tends to oppose upward movement of the bar 80 with respect to the coupling member. On the pin 83 is pivoted a pawl 84 having at its 35 end a locking tooth adapted to engage teeth 75 of a stationary locking bar 14. The pawl is provided with a roller engaging in a cam slot 98 in the shoulder of the coupling member. Upon a stub shaft 100 projecting from the shoulder 40 of the coupling member is pivotally mounted an interlocking wheel 105, which consists of a pinion 108 meshing with the teeth 77 of the driving member and a semi-circular locking rim 107 45 which cooperates with a flat face 86 and a curved face 87 of the differential member 80. The coupling member, driving member, and differential member are all slotted to receive stationary guide bars 10 and 71 upon which they are guided in their vertical motion. All of the driving members 50 are fixed to a transverse bar 110 which is connected by mechanism not shown with a cross head 115 near the top of the machine. This cross head is given a downward and upward reciprocation at each operation of the machine by 55 a driving mechanism not shown. As the driving member starts to move down the coupling member and differential member 80 are carried along with it due to the interlocking of the wheel 105 and the action of the spring 99. When the differential member 65, 80 is stopped by one of the keys, the coupling member at first continues to move down with the driving member, the flat face of rim 107 gliding along with the flat face 86 of the differential bar. When the rim 107 60 comes clear of the face 86 the interlocking wheel is free to turn, the coupling member is arrested, and further downward movement of the driving member simply rotates the interlocking wheel 105. During the relative movement of the coupling member and differential bar 80, the cam slot 98 swings pawl 84 into engagement with one of the teeth 75 of locking bar 14, which locks the differential member in its set position. The differential bar 80 is provided with a shoulder 111 70

and the coupling member 81 with a similar shoulder, both cooperating with the cross bar 110. When the driving member and cross bar 110 move upward during the further operation of the machine, the cross bar 110 first comes into engagement with the shoulder of the coupling member, which, it will be remembered, moved down slightly below the differential bar 80. At the instant of engagement the flat face of rim 107 has come into alignment with the face 86 of the differential bar, so that the coupling member is free to move up while the differential bar remains locked temporarily. The upward movement of the coupling member swings pawl 84 away from locking bar 74 and when cross bar 110 strikes shoulders 11 of the differential bar 80, the latter is free to move upward with the driving member and coupling member to its starting position.

The upper end of the coupling member is provided with a series of teeth 137 arranged opposite a series of teeth 135 on the upper end of a setting member 82 which controls the position of the display and printing wheels. Interposed between the teeth 135 and 137 is a pinion 136 having a hub 139 which cooperates with a stationary rest 140 and with a shoulder 141 on the reciprocating cross head 115. When the setting member 82 takes its lower end position, which corresponds to the zero position of the display and type wheels, and the coupling member 81 takes its upper end position, the hubs 139 are a certain distance away from the recess 140. This distance amounts to half the distance travelled by the coupling member after the differential member is stopped as described above. Consequently when the setting member 82 and differential member 65, 80 are in zero position and the coupling member has moved downward to the point where it becomes locked with the differential member, the hub 139 will rest in the recess 140. Then when the cross head 115 is moved downward until it engages the hub 139, no adjustment of the setting member 82 will take place and the display and printing wheels will remain in zero position. Upon setting an amount key, for instance the 6 key, the differential and coupling members move down six units and the latter then moves the short distance further required for its locking with the differential member. The differential wheel 136 starts to roll down with the coupling member, but is soon arrested by engagement of its hub with the recess 140. Further downward movement of the coupling member rotates the wheel 136 and thereby raises a setting member 82. It will be evident that the setting member is thus raised six units. Upon the return movement of the differential mechanism the coupling member moves upward six units plus the locking distance. During this movement the differential wheel 136 rolls upward along the setting member, which remains stationary, until its hub 139 has moved upward from recess 140 for a distance corresponding to six units movement of the coupling member plus its locking movement.

In the next operation of the machine, assuming the number set to be larger, for instance 9, the hub of the differential wheel first moves downward a distance corresponding to six units movement of the coupling member, plus the locking distance, and there engages the recess 140. Further downward movement of the coupling member for three units causes the differential wheel to rotate and move the setting member 82 upward three units. On the other hand, if the

subsequent number to be set is smaller than six, for instance 2, the coupling member is locked after it is moved downward two units plus the locking distance, leaving the differential wheel still above the recess 140 by a distance corresponding to four units. The hub of the differential wheel is thereupon engaged by shoulder 141 of the cross head 115 and is thereby moved down to the recess 140, bringing the setting member down four units to the two position. In this way the setting member is left in its set position after each operation and in the next operation is moved directly to its new position.

The totalizers

The account totalizers N₁, N₂, N₃ and the transaction totalizers S consist of totalizer wheels grouped upon the several shafts 161 by decimal orders. On each shaft totalizer wheels of the same order of all the totalizers on the shaft are arranged in a group, and for each group there is a differential wheel 154 permanently connected to the corresponding differential member 65, 80, as previously described, and adapted to be selectively coupled to one of the totalizer wheels in its group. The mechanism for effecting this coupling is similar to that of the main and auxiliary totalizers and will therefore not need special explanation here.

The main and auxiliary totalizers shown in Figs. 29 and 30 are of the same construction and will therefore not require separate description. The corresponding parts in these two totalizers are given the same numbers with the distinction that those of the main totalizer are primed. The totalizers have adding wheels 219 and subtracting wheels 220, each fixed by pins 218 to respective bevel wheels 216, 217. The bevel wheels are rotatably mounted upon extended hubs 215 of differential wheels 214. Bevel pinions 226 pivotally mounted on sleeves 228 connect the bevel wheels so that they rotate in opposite directions. Within the aligned hubs of the differential wheels 214 is a longitudinally slidable shaft 224 slotted within the boundaries of each hub to receive a rider 223. Each hub is longitudinally slotted at 222 and the rider 223 has a tooth projecting through the slot and for a short distance beyond. The rider is free to rotate in the slot of shaft 224, but its longitudinal position is determined by that of the slot. The bores of wheels 219 and 220 are provided with recesses 221 to receive the tooth of the rider 223. The shaft 224 has three positions, a neutral position shown in Fig. 29, in which the rider is out of engagement with both counting wheels, an adding position, where the rider is in engagement with the adding wheel 219, and a subtracting position, where the rider is in engagement with the subtracting wheel 220. When the rider is engaged with either counting wheel and motion is imparted to differential wheel 214 from the differential member 80, the rider rotates with the differential wheel and turns the counting wheel accordingly. Reverse rotation is imparted to the counting wheel not engaged by the rider by pinion 226. The outer peripheries of the counting wheels are provided with recesses 229 engaged by teeth 230 on rocking arms 170 while the riders are being shifted, thus aligning the counting wheels so that the tooth of the rider can pass freely within the recesses 21.

Parallel to shaft 224 is a shaft 236, the two being rigidly connected by a cross piece 238. This cross piece has an arm 308 engaged by a shaft 75

311 by which the adjustment of the shaft 224 is effected in a manner to be presently described. Within the bounds of each order of the counting wheels is rotatably mounted on the shaft 236, a bracket 235. Within each bracket there is rotatably mounted on the shaft 236 a tens transmitting and zero stop tooth 233 having recess 234 embracing the bracket 235. The tooth 233 is held in a definite position on shaft 236, opposite the corresponding rider 223 by collars 237, and is therefore aligned with the selected counting wheel by the simultaneous adjustment of shafts 224 and 236. The intermediate pinions 164, 165 are pivotally supported on the end of a rotatably mounted arm 163. The rear end of the arm 163 has a cam slot engaged by a roller 185 mounted on an extension 187 (similar to 187a, Fig. 30) of bracket 235. This extension is provided with a sector of teeth engaging a pinion 191 to which is fixed an arm 193. The latter is pivoted by a pin 192 to an arm 194 connected at its opposite end to a bow piece 197 rotatably mounted on shaft 196. One end of a spring 198 is connected to shaft 196 and the opposite end to bow 197.

25 Each counting wheel is provided with a long tens transmitting and zero tooth 232. The counting wheel being actuated is turned in counter-clockwise direction as viewed in Fig. 30. In the zero position tooth 232 is just above tooth 233.

30 In passing from 9 to zero the tooth 232 raises tooth 233 and thereby tilts bracket 235 in clockwise direction. Segment 187 is thereby rocked clockwise and turns pinion 191 far enough to bring the pin 192 across dead center position, 35 whereby spring 198 draws the arm 194 downward causing further clockwise movement of bracket 235. The final position of the parts is shown in the lower totalizer in Fig. 30. During the rocking of bracket 235 the roller 185 travelling in the cam slot of arm 163 has caused that arm to tilt counter-clockwise far enough to impart a one unit movement to the differential wheel 214 of the next higher order, through the action of intermediate pinions 164, 165.

40 The shaft 196 is provided with rigid arms 200 engaging pins 205 on the rocking arms 187. During each operation of the machine the shaft 196 is rocked by a mechanism not shown to swing arms 200 upward and thereby restore the tens transfer mechanism to normal position shown in the upper totalizer in Fig. 30. In this position pin 192 has passed dead center position and the arm 194 is held against shaft 196 by the action of spring 198.

45

55 Taking positive totals

In the zero position of the counting wheels the zero tooth 232 of the adding wheel is just above the zero stop tooth 233, while the zero tooth 232 of the subtracting wheel is just below the tooth 233, as shown in Fig. 30. When a positive total is to be taken the adding wheel is coupled to the differential wheel by adjustment of rider 223 and the differential member 80 is moved downward until it is arrested by abutment of the zero tooth 232 of the adding wheel against the zero stop 233 from above. The position of the differential member, and consequently of the setting member 82 and display and printing wheels, is thereby determined by the number of units of rotation imparted to the adding wheel to bring its zero tooth against the zero stop 233.

Mechanism for drawing negative totals

75 Negative totals are drawn by coupling the differential wheel 214 with the subtracting wheel

220, which also positions the zero stop 233 opposite the subtracting wheel, and by moving the differential bar 80 downward until it is stopped by abutment of the zero stop tooth 232 against the zero stop 233 from above. If the totalizer 5 stands at zero, in which position the zero stop teeth 232 of the subtracting wheels are all just below the zero stops 233, and if the amount -1 be then transmitted to the totalizer, the subtracting wheel of the units order, at the right hand 10 end in Fig. 29, will be rotated counter-clockwise by one unit, thus tripping all the tens transfer devices and moving all the other subtracting wheels up one unit. If the total should now be taken by turning the subtracting wheels back 15 until the zero stop teeth 232 strike the zero stops 233, the result would be zero, instead of -1 , as it should be. It is therefore necessary to transmit an additional unit to the units subtracting wheel when the total passes from zero to -1 . 20 The tens transfer mechanism of the highest order is utilized for this purpose and it is modified to the extent that it is not coupled to a rocker arm of a higher order, but to the rocker arm of the units order. The mechanism is designed so that the unit is only imparted to the units order upon a passage from zero to -1 , or vice versa, and not when the limit of the totalizer is exceeded in a positive or negative direction.

The rocking piece 187a of the highest order 30 furthest to the left in Fig. 29, is provided with a tail 241 coupled by a pin 240 to the slotted end 242 of a link 243. The opposite end of the link is pivoted to an arm 245 fixed on the shaft 244. In front of the units order are arranged the tens transmitting devices 163, 164, 165, 185, 187b, 191, 192, 193, 194, 197 and 198, similar to those of the other orders. The wheels 164, 165 connect the differential member 80 to the differential wheel 214 of the units position. The rocking piece 187b 40 has a tail 246 (Fig. 29) like the tail 241 of the rocking piece 187a in highest order, and the tail 246 is connected to a rigid arm 250 on the shaft 244 by the pin and slot connection 247, 248 and link 249. Upon a passage from zero to -1 , which 45 trips the transfer devices of the highest order, the shaft 244 is rocked by the rocking member 187 and thrusts the link 249 forward, thus tripping the transfer devices for moving the intermediate wheels 164, 165 coupled to the differential wheel 214 of the units order downward and thereby imparting a motion of one unit to the units subtracting wheel. Thereupon when the total is taken, the units subtracting wheel being advanced one unit, the zero stop 232 will be correctly positioned with respect to the zero stop 233 to stop the differential member 80 in the proper position. When the totalizer has arrived at zero from a negative direction and the amount $+1$ is transmitted to the adding wheel, the same transmission of an additional unit to the units adding wheel occurs as took place with the units subtracting wheel upon a passage from zero to -1 . 55

The supplemental unit is to be added to the adding or subtracting wheel of the units position 60 only when the totalizer is passing from a negative to a positive value, or from a positive to a negative value. Since the mechanism for adding the supplemental unit is controlled by a mechanism in the highest order of the totalizer in 70 the nature of a transfer mechanism which is tripped every time the counting wheel moves between positions 9 and 0, it is necessary to prevent the transmission of a supplemental unit to the units order when this mechanism is tripped 75

by a passage of the highest numeral wheel to zero when the capacity of the totalizer is exceeded. For this purpose the following mechanism is provided: Upon the right hand end of shaft 244 in Fig. 29 is loosely mounted a hub 259a upon which are rigidly fixed two spur gears 259 and 260 and a ratchet 255. Inside the hub 259a there is fastened to the shaft 244 an arm 256 bearing at its end a pawl 257 which engages the ratchet 255. When shaft 244 is rocked by the tripping mechanism of the highest order of the totalizer pawl 257 advances ratchet 255 for a distance of one tooth, thereby turning spur gears 259 and 260. Upon a stub shaft 261a mounted 10 on the frame of the machine is rotatably supported a hub 261 bearing a fixed spur gear 262 meshing with gear 259. Upon the hub 261 are two pairs of lugs 267a and 267b, the two pairs being arranged in two different planes transverse to the axis of the hub. The lugs of each pair are 180° apart and the lugs of one pair are at right angles to the lugs of the other pair. These lugs cooperate with a finger 268 on the cross-bar 238 which adjusts the coupling of the 20 adding and subtracting wheels of the totalizer. The position shown in Fig. 29 is the neutral position, the rider 223 being disengaged and finger 268 being clear of both pairs of lugs 267a and 267b. When shaft 224 moves into the position 30 in which rider 223 is coupled to the adding wheel 219, finger 268 comes into the plane of lugs 267b. When the rider 223 is coupled to the subtracting wheel 220, the finger 268 is moved into the plane of lugs 267a. 35 The operation is as follows: Assuming the totalizer to be negative, the lugs 267a and 267b will have the position shown in Fig. 29. If negative values are now added to the totalizer, finger 268 will be moved into the plane of lugs 267a and 40 one of these lugs will be just above the finger 268. If the negative amounts inserted in the totalizer should cause the subtracting wheel of the highest order to pass from 9 to 0, the rocking member 187a will be rocked and will move link 45 194 across dead center position, where spring 198 tends to pull it down and rock 187a, 243, and shaft 244. However, shaft 244 is prevented from rocking by abutment of one of the lugs 267a on finger 268; therefore no supplemental unit is 50 transmitted to the units order. On the other hand, if the rider 223 is engaged with the adding wheel 219 for insertion of a positive amount exceeding the negative balance in the totalizer, the rocking member 187a of the highest order will 55 be tripped by the transfer tooth 232 of the adding wheel. At this time the finger 268 will lie in the plane of lugs 267b, the nearest of which will be 90° away from finger 268. Consequently shaft 244 will be permitted to rock and transmit a 60 supplemental unit to the adding wheel of the units order. With the lugs 267a and 267b in the new position, further oscillations of shaft 244 while the adding wheel of the totalizer is coupled will be prevented by engagement of lug 267b with 65 finger 268, but if the subtracting wheel is coupled and the totalizer moved to a negative balance, finger 268 will lie in the plane of lugs 267a, the nearest one of which is 90° away. Thus a supplemental unit will be transmitted to the subtracting wheel of the totalizer. 70

In the frame of the machine is rotatably mounted a shaft 264 (Fig. 29) upon which are fixed a gear 263 meshing with gear 260 and a control disc 265. The disc 265 has two sectors 75 of large diameter and two sectors of small diam-

eter (Fig. 4). Each time the totalizer passes from positive to negative, or from negative to positive, the disc 265 is turned 90°. The disc 265 for the auxiliary totalizer is shown in the position corresponding to a positive total in Fig. 4. 5 The control disc 265' of the main totalizer is shown in the position corresponding to a negative balance in the totalizer. The control discs 265 and 265' are utilized in drawing totals to control the position of the shaft 224 and 224' in 10 accordance with the sign of the total, and also to control a printing wheel for printing the sign of the total. 15

Totalizer control mechanism

The operation of the totalizers is controlled by five shafts, shown in Figs. 4 and 32, differentially adjustable as to angular position. The upper three shafts 273 control the selection of the account totalizers. Shaft 274 controls the selection of the transaction totalizers, the selection of the adding or subtracting wheels of the main and auxiliary totalizers, and the coupling or non-coupling of the auxiliary totalizer. Shaft 370 controls the coupling or non-coupling of the 20 main totalizer. These shafts are adjusted by a differential mechanism controlled by the banks of keys 11, 12 and 13. The bank 11 controls shaft 274. The bank 12 controls shaft 370. The banks 13 control shafts 273. The differential 30 mechanism cooperating with these banks of keys is similar to the amount differential mechanism and it will therefore be necessary only to describe it briefly and to point out the differences. Reference will be made principally to Fig. 3 35 which shows a horizontal section through the differential mechanism just above shaft 274, with a small insert of a plan view of the differential mechanism cooperating with the bank of keys 11 and with the left hand bank of keys 13. The 40 parts of this differential mechanism are given the same reference characters as the amount differential mechanism, with the addition of a prime mark. The differential mechanism for each bank of keys comprises two groups of vertical bars, some of which are vertically slidable. Taking the group at the left, which cooperates with the key bank 11, there is a differential member composed of two connected parts 251, 250'. The part 251 corresponds to the part 65 of the 50 amount differential mechanism and cooperates with the shafts of the keys to limit the motion of the differential member. In addition to the differential member there is a driving member 76', a coupling member 81', a locking bar 74', and a setting member 82', just as in the amount differential mechanism. In addition to these there is an adjusting bar 278 connected to the foot of setting member 82' by a rigid arm 278a, the bar 278 being provided on its rear edge with a 60 series of teeth engaging a pinion 277 fixed to shaft 274. By these connections the position of shaft 274 always follows that of setting member 82'. 65

The differential mechanism on the extreme right cooperating with the key bank 12 contains an adjusting bar 278' in mesh with a pinion 277' on shaft 370. The adjusting bars 278 of the three middle differential mechanisms are respectively connected to three pinions 277 fixed upon the three shafts 273. Fig. 3 shows the part 253 of the differential member which cooperates with the left bank of keys 13. In the three differential mechanism on the right the section in this figure is taken below the part of the differential 70 75

member which cooperates with the keys, so that this part does not appear in these banks.

The end of shaft 274 is square (Figs. 3 and 31) and projects slidably into a square aperture in a drum 272. This drum is positively connected to shaft 161 of the transaction totalizers in a way which permits it to rotate without relative longitudinal motion with respect to the shaft 161. The longitudinal position of shaft 161 is thus determined by that of the drum 272. The drum has on its surface helically arranged steps 281 which cooperate with a finger 295 (Fig. 3) on a sliding bolt 291 to determine the longitudinal position of the drum. In each operation of the machine 10 the finger 295 is moved to the left and brings the step 281 which is brought into line with it by the angular adjustment of drum 272 up against a stop 297 (Fig. 31), thereby coupling the proper set of totalizer wheels of the transaction totalizers with 15 the differential wheels. For shifting the bolt 291 there is provided a vertical rotatably mounted shaft 284 (Figs. 3 and 4) having fixed to it arms 290. One of these arms is connected by its forked end with the bolt 291 cooperating with the drum 272 for the transaction totalizers. The other 20 arms are connected to other bolts 291 cooperating in the same way with drums 272 for the account totalizers. On the shaft 284 is a bevel wheel 285 meshing with a bevel sector 286. The latter is 25 fixed to a rocking member 287 having teeth meshing with a corresponding segment 288 on a drive shaft 289. A rocking motion is imparted to the drive shaft 289 by a mechanism not shown.

The shaft 274 has other functions besides adjustment of the transaction totalizers; it also serves to determine the coupling or non-coupling of the auxiliary totalizer, and in some cases the adding or subtracting position of the main and auxiliary totalizers. The coupling of the main 30 totalizer is controlled by shaft 370. The mechanism whereby this is accomplished is shown in Figs. 3, 4, 26, 27, 31 and 32. Since the mechanism is largely the same for both the auxiliary and main totalizers a description of one will serve 35 principally for a description of both. A shaft 311' rotatably and slidably mounted in the frame of the machine is connected to shaft 224' of the main totalizer by an arm similar to arm 303 in Fig. 29, the connection between the arm and shaft 311' being a socket joint which permits rotation of shaft 311', but which prevents relatively longitudinal movement between shafts 311' and 224'. On shaft 311' are two steps 309', 310' (Fig. 31) corresponding respectively to the subtracting and 40 adding positions of the main totalizer. Surrounding shaft 311' is a sleeve 318' having on its surface two steps 323' and 324'. These steps cooperate with a finger 295 (Fig. 4) on a bolt 291 to which a shifting motion is imparted by arm 308 (Fig. 4) on a sleeve rotatably mounted on a shaft 284, bevel gear 305 on said sleeve, bevel sector 306, toothed sectors 307 and 308, and a drive shaft 304 driven by mechanism not shown. The sleeve 318' has an extension 326' upon which is mounted a collar 325' lying outside of the steps 309', 310'. The steps 309', 310' or collar 325', as the case may be, are brought up against an abutment 317' by the action of finger 295, to determine the longitudinal position of shafts 311' and 224'. When sleeve 318' is in the angular position shown in Fig. 31 the collar 325' is out of the path of abutment 317' and the position of shaft 311' is determined by steps 309' and 310'. When the sleeve 318' is rotated to its other position the 55 collar 325' comes into line with abutment 317'.

and determines the position of shaft 311' without regard to the position of the steps 309', 310'. This latter position of sleeve 318' corresponds to the neutral position of shaft 224'. When finger 295 moves back it strikes lug 327' and brings shaft 5 224' back to neutral position.

The angular position of shaft 311', which determines the setting of steps 309', 310' and thus the adding or subtracting position of shaft 224', is determined by a mechanism shown in Figs. 3, 10 27, 31 and 32. The corresponding mechanism for the auxiliary totalizer is shown in Fig. 26. An arm 312' fixed on shaft 311' is connected by a pin 313' with the slotted end of a bell crank lever 315' rotatably mounted on shaft 314. The 15 other arm of the bell crank lever is pivoted to a slide 316'. At one end the slide 316' is embraced by a fork 387 which is fixed to a shaft 386 and thereby positively swung at each operation of the machine, shaft 386 being rocked by the driving 20 mechanism of the machine. Between the fork 387 and a shoulder 388 on slide 316' is a spring 389. At the opposite end the slide has an outwardly bent lug 412' cooperating with the surface of a control disc 408 on shaft 274. This control 25 disc has sectors of large diameter corresponding to an adding position of slide 316' and sectors of smaller diameter corresponding to a subtracting position. If one of the larger sectors is opposite lug 412' when fork 387 swings inward, the slide 30 316' cannot move and the bell crank 315' and shaft 311' remain in the same angular position shown in Fig. 27, which positions the adding step 310' in the path of finger 295. If one of the sectors of smaller diameter of control disc 408 is 35 opposite lug 412', the slide 316' moves inward swinging bell crank 315' and shaft 311' and bringing the subtracting step 309' into the path of finger 295.

When control disc 408 is moved into the angular 40 position corresponding to the key RZ (sub-total from the main totalizer) the positioning of the totalizer coupling mechanism is controlled by the totalizer in accordance with the sign of the total therein. For this purpose a second control disc 411 is rotatably mounted beside the disc 408 and is resiliently held in a certain angular relation to shaft 274 by a spring 415'. The disc 408 has a recess at the sector corresponding to the key RZ, but in the normal position of disc 411 the lug 412' on slide 316' is prevented from entering this recess by the disc 411. Rotatably mounted on shaft 370 is a bow 419'. Pivoted to one end of the bow is a thrust rod 421', the lower end of which is provided with a slot whereby the thrust rod is slidably supported on shaft 264'. Pin 423' on thrust rod 421' cooperates with control disc 265' to prevent the thrust rod from moving downward if a high part of the control disc is presented, or to permit the thrust rod to move downwardly if a 50 recess is presented. The thrust rod 421' is normally urged upward by a spring 424'. On control disc 411 is a nose 417' adapted to engage a pin 418' on the bow 419'. The mechanism operates in the following manner: When the key RZ is 55 depressed the shaft 274 is rotated by the differential mechanism until the recess of control disc 408 normally covered by control disc 411 is brought opposite lug 412', the disc 411 being rotated simultaneously through the action of 60 spring 415'. The nose 417' strikes pin 418' and if the thrust rod 421' is locked by disc 265', the control disc 411 is stopped and the recess of disc 408 arrives opposite lug 412' uncovered by disc 411. Thus the slide 316' is permitted to move to the 75

left and swing shaft 311' to subtracting position. On the other hand, if a recess of disc 265' is presented to the pin 423', the nose 417' swings bow 419' and thrust rod 421' downward so that the control surface of disc 411 arrives opposite lug 412'. In order that this may take place the spring 415' is made stronger than the spring 424'. Then when the fork 387 is swung to the left the slide 316 is locked against leftward movement and shaft 311' remains in adding position.

The position of sleeve 318' which controls the throwing in and out of the main totalizer is determined by a control disc 407 on shaft 370 and a slide 322' (Figs. 3 and 32) similar to the slide 316'. Slide 322' is connected to sleeve 318' by a bell crank lever 321', a pin 320' and an arm 319' on the sleeve.

The adding and subtracting control of the auxiliary totalizer is taken from control discs 405 and 410 on shaft 274 by a mechanism in all respects similar to the control mechanism for the main totalizer. The throwing-in and out of the auxiliary totalizer is controlled by a disc 405 fixed on shaft 274 and a lever 409 pivotally mounted on shaft 274 and operated directly by the key HR. The lever 409 has a segment which blocks out control slide 322, even when a recess of disc 405 is presented to the slide, unless lever 409 has been moved by depression of the key HR to remove its segment from the path of slide 322. The connections between slide 322 and sleeve 318 comprise a bell crank lever 321, a pin 320, and an arm 319 on the sleeve.

35 The type wheels of the printing mechanism

The printing type are rigidly mounted on type wheels which are mounted in two groups coaxially with the shafts 520, 521 (Figs. 5, 15, 16). Each type wheel carries two sets of type, one set being arranged on the upper half of the wheel, and the other set on its lower half. By this means four printing places are formed in the printing mechanism each designed for printing a special document, viz. the record strip, the customer's receipt, the book and the account card.

45 The record strip receives all the transactions made by the machine and required for controlling the operations, the receipt serves for a single proof of the transaction, the book and the account card serve for collective proof of the transactions made in an account. While the book is retained by the customer, the card remains in the bank.

55 The rear four type wheels 522, 522' (Fig. 5) of each group of type are used for printing the consecutive number and are actuated by means of a special mechanism, described hereinafter, that causes the wheels 522, 522' to be advanced one unit each operation of the machine.

60 The next ten type wheels 523, 523' (Fig. 5) of each group are the amount type wheels. They are connected by tubular shafts 524, 524', surrounding each other, to spur wheels 525, 525', which, in turn, are in mesh with racks 526 mounted so as to be shiftable laterally in the machine. The racks 526 are guided by slots 556, 557 (Fig. 10) into which project bars 558, 559 mounted in the frame and carrying, between the racks 526, spacing collars 560 (Fig. 5). Wheels 528 rigidly journalled on shafts 527 mounted in the frame are in mesh with teeth 550 (Fig. 10) arranged on the upper surface of the racks 526. The shafts 521 carry, at their rear end, spur wheels 529 (Figs. 5, 2) in mesh with the teeth 146 of the members 82 of the amount differential mechanism.

As described, said members are differentially positioned during the operation, to the amount set up on the keyboard or to the amount on a totalizer selected for total taking.

The next six type wheels toward the front 530 to 535 and 530' to 535' (Fig. 5), are allotted to the transaction totalizers and to the + and - sign printing mechanism. They are mounted loosely on the shafts 520, 521 and have rigidly mounted on them teeth 536 in mesh with toothed 10 wheels 537, 537'. The front wheels of each of these groups are rigidly connected to shafts 538, 539, respectively, and the remaining wheels with tubular shafts 540 surrounding one another. The rear ends of the shafts 538, 539 and of the tubular 15 shafts 540 carry spur wheels 541, 541' engaging racks 542 to 547. These racks show slots 551 (Fig. 10) and 548 (Fig. 11) by means of which they are guided for lateral movement on bars 560, 549 rigid on the frame. 20

The rack 542 (Fig. 5) connected to the type wheel's 530, 530', has a lateral lug 561 (Figs. 3 and 4) which engages, by teeth 562, a segment 565. This segment is mounted on a carrier 563 of the frame 23 of the machine and has pivoted to it a rod 439 (Figs. 4, 5) which is connected to the setting device for the + and - signs. The type wheels 530, 530' carry within their two printing zones the signs plus and minus (Fig. 28). In order to print the minus sign beside the amount, upon printing a negative amount, the following arrangement is provided.

The totalizer governing mechanism, as previously described, contains two controlling slides 316 (Fig. 26) and 316' (Fig. 27), which govern 35 the positioning of the main and the auxiliary totalizers for addition and subtraction, and for positive and negative totals.

Said controlling slides 316 (Fig. 26) and 316' (Fig. 27) are provided with slots 434, 434' against 40 the right-hand walls of which abut pins 435, 435' carried on arms 437, 437' fixed on a shaft 436. A bell-crank 438 is secured to the shaft 436 and is connected to the rod 439 which as above mentioned, is connected to the type wheels 530, 530' 45 of the printing mechanism. An arm 441 of the bell-crank has on its end a roller 440 which abuts, in the initial position of the parts, against the periphery of a cam disk 443 fixed on a shaft 442 (Fig. 4). In this position of said arm 441 50 50 the plus sign of the type wheel is in the printing position. During the operation of the machine an anti-clockwise rotation is imparted to the disk 443. At the moment when the upper opening 444 of the curved groove 445 is opposite the roll 55 440, the driving movement for the controlling slides takes place. Upon one of the slides 316 or 316' herewith being moved to the left, which is the case in subtracting or in taking a negative total, the corresponding pin 435, 435' is pulled 60 to the left, whereby the roll 440 enters the curved groove 445 and is kept there during operation of the printing mechanism. Movement of arm 441 to this position causes the minus sign of the type wheel to be brought to printing position. 65 The racks 543 to 547 (Fig. 11) each have upper teeth 566 meshing with a wheel 567 (Figs. 11, 3) fixed on a shaft 568 mounted in the frame. These shafts 568 carry on their rear ends wheels 569 (Fig. 3) which are in mesh with the positioning 70 members 82' of the transaction totalizers. The described connections cause the type wheels 531, 531' to be positioned by the keys of row 11, the type wheels 532, 533, 534 and 532', 533', 534' by the keys of row 12, and the type wheels 535, 535' 75

- by the keys of row 12. The type wheels carry type appropriate to the keys of said rows.
- The next four type wheels toward the front, 570, 570' (Fig. 5), serve for printing the date.
- 5 They carry teeth 571 engaged by wheels 572, 572' mounted coaxially with the shafts 538, 539. The wheels 572 are rigidly fixed on sleeves 573 which are provided at their front end with setting wheels 574 (Figs. 1 and 5) for setting the date.
- 10 The wheels 572', loosely mounted on the shaft 539, are in mesh, by intermediate wheels 576 mounted on a shaft 575, with the wheels 572 so that the date type wheels 570, 570' can be set correspondingly by the setting wheels 574.
- 15 The foremost seven type wheels 571, 571' (Fig. 5), mounted for free rotation on the shafts 520, 521, are used for printing the number of the account as set up on the keys 11 (Fig. 1). Each wheel 571 is in line with a corresponding wheel 571', and the same is true of gears 578 rigidly fixed to the wheels. Each pair of gears 578 is in mesh with one of a series of racks 579 (Figs. 20, 5) mounted for lateral shifting in the frame by means of s'ots 580 and cross bars 581. The 25 right-hand ends of these racks 579 have teeth 582 meshing with toothed wheels 584 rigidly mounted on shafts 583. These shafts 583 are rotatably mounted on the frame and have toothed wheels 585 (Fig. 4) secured to their rear ends. These 30 latter are in engagement with toothed wheels 586 (Figs. 4, 5) of differential shafts 587. The differential shafts 587 are rotatably mounted in the frame (Fig. 20) above the shafts 583 and carry stops 588 arranged helically which stops cooperate with the ends of the shafts 589 of the keys 17 (Fig. 4). The toothed wheels 585, 586 and the stops 588 in adjacent positions are staggered with reference to each other, as shown in Fig. 5, in order to prevent interference. The key shafts 40 589 carry pins 590 which cooperate, like the pins of the amount keys, with a locking bar 591 having hook-shaped portions, and with a block bar 592 having V-shaped recesses. These two bars are shiftably mounted on cross bars 594, 595 by 45 means of s'ots 593. Toothed wheels 596 (Figs. 19, 5) are loosely mounted on shafts 583 and are connected impositively, by springs 597 (Fig. 5) to the shafts 583. Springs 597 normally hold lugs 598 (Fig. 19) on wheels 596 against rigid stops 50 599 on shafts 583 (Fig. 32).
- The toothed wheels 596 are in mesh with a common rack 600 (Figs. 19, 5) which is guided by slots 605, 606 for lateral shifting on bars 607, 608. A rod 609 connects the rack 600 to a lever 611 (Figs. 19, 6) mounted on a shaft 610. The lever 611 cooperates, by means of rolls 612, 613, with two cam disks 614, 615 rigidly mounted on the main driving shaft 616 of the printing mechanism.
- 55 60 When the rack 600 is moved to the right by rotation of the disks 614, 615, a rotation is imparted to the toothed wheels 596, which rotation is partaken of by the shafts 583, owing to their being coupled thereto by the springs 597 (Fig. 5), until one of the stops 588 of the corresponding shaft 587 strikes a foot of the depressed key 11. The type wheels 571, 571' of the corresponding row of keys 11 are thereby set to the value of the depressed key. When in position of rest the type 65 wheels 571, 571' are at zero. If no key 11 is depressed in one of the rows, the corresponding differential shaft 587 has a full revolution imparted to it, said revolution being limited by a fixed stop 617 (Fig. 5) cooperating with the differential shaft 587. This complete revolution imparts a
- half revolution to the type wheels 571, 571', because of the transmission ratios between the wheels 586, 585, 584, 578. After the printing operation the differential shafts 587 and the type wheels 571, 571' are returned to their initial position by the disks 614, 615.
- The drive of the printing devices*
- The printing shaft 616 is connected to the main driving shaft 42 (Figs. 3, 4, 8) of the machine by a pair of bevel wheels 620, 621 and spur wheels 622, 623, 624. Upon each rotation of the shaft 42 a full revolution is imparted to the shaft 616. As will be seen from Figures 2 and 6, the shaft 616 carries, besides the disks 614, 615, a series of cam disks for driving the other parts of the printing mechanism. These devices include the feeding mechanism for the control strip, the receipt, the account book, and the card, and include the cutting device for the receipt and the driving mechanisms for the printing plates and the ratchet device for the consecutive number.
- The rear disk 626 (Fig. 6) has a curved groove 627 which (Fig. 12) engages a roll 628 of a rod 630 embracing its forked end, the shaft 616, and pivoted at its other end to a bell-crank 629. The bell crank 629 is secured on a shaft 631 having also secured thereon a lever 632 (Fig. 6). The upper arm of the angle lever 629 and the arm 632 are connected by a rod 633 which projects through slots 634 (Figs. 14 to 18) lying concentric to the shaft 631 and cut in seven arms 635 loosely mounted on the shaft 631. The rod 633 has an offset portion 633' (Fig. 6) to prevent interference with the movements of a toothed wheel 672 described hereinafter. These arms 635 are impositively connected to the rod 633 by springs 636 in such a manner that the upper wall of their slots 634 normally abuts the rod 633. The left-hand ends of the arms 635 have pivoted on them, by pins 637, controlling slides 638 embracing, with their fork-shaped lower ends, a guiding rod 639 mounted in the frame of the machine. Each controlling slide 638 carries on its upper end a cross piece 640 having two lateral lugs 641, 642. The cross pieces 640 are pivotally connected to the slides by the pins 637, with the exception of the fourth and fifth slides from the rear, which are rigidly connected to their cross pieces.
- The lateral lugs 641, 642 of the controlling 50 slides cooperate with fourteen controlling disks, in particular with controlling disks 643 to 649 (Fig. 6) rigidly fixed on a shaft 650 and with controlling disks 651 to 657 rigidly fixed on a shaft 658 (Figs. 10, 6 and 14-18). The latter carries a toothed wheel 659 connected, by means of a toothed wheel 661 loosely mounted on a shaft 660, with a toothed wheel 663 rigidly mounted on a shaft 662. This latter carries at its rear end a toothed wheel 664 (Fig. 5) engaged by the rack 60 55 547, the position of which is controlled by the member 82 allotted to the row of keys 12 (Fig. 1). In a similar manner the shaft 650 is in connection with the rack 643, attached to the member 82' of the row of special keys 11, by means of 65 toothed wheels 671, 672 (Fig. 10), 673 (Fig. 5), by a sleeve 674 (Fig. 5) surrounding the shaft 642 and a toothed wheel 675 fixed to the rear end of the sleeve 674.
- As described in said copending application the 70 positioning member 82' of the row of keys 11 is in connection with the controlling shaft 274 (Fig. 4) and the positioning member of the row of keys 12 to the controlling shaft 370, so that in selecting the transaction totalizer, the shaft 75

650 is positioned in correspondence to the controlling shaft 274 and the shaft 658 in correspondence to the controlling shaft 370.

The controlling slides 638 carry at their lower end pins 680 (Fig. 10) engaging slots 681 of links 682 (Figs. 10, 13), 683 (Fig. 14), 684 (Fig. 16), 685 (Fig. 15), 686 (Fig. 17), 687 (Fig. 18) and 688 (Fig. 20). The curved groove 627 (Fig. 12) is of a shape such as to cause the rocking frame 631, 10 633 to have imparted to it a rocking motion, after the shafts 650, 658 have been positioned in accordance with the transaction totalizer selected. Upon this rocking motion taking place, the controlling slides 638 are pressed impositively with 15 the lugs 641, 642 of their cross pieces 640 against the periphery of the disks 643 to 649 and 651 to 657 (Fig. 6). Those of the controlling slides the lugs 641, 642 of which are, when this takes place, opposite to recesses of the controlling disks, are 20 taken along downward and swing downwards the links 682 to 688 engaged by their pins 680 and mounted on arms 690 of a shaft 689. In so doing, the links 682 to 688 come to engage by recesses 691 a rod 692 (Figs. 14 to 18) and, respectively, 25 pins 693 (Fig. 13) or 694 (Fig. 20) which are driven by the shaft 616 in a manner hereinafter described.

The rod 692 (Fig. 6) is carried by two arms 695 rigidly connected to one another by a sleeve 696. 30 This sleeve is mounted on a shaft 701 and is connected to arms 697, 698 (Fig. 14) carrying rolls 699, 700, cooperating with cam disks 705, 706 fixed on the shaft 616. With the rod 692 cooperate the five links 683, 685, 684, 686, 687 (Figs. 35 14 to 18) which are destined for driving the receipt cutting device, the printing platens for the book, the card, control strip and ticket.

The pin 693 (Fig. 13) is carried by one arm 707 of a three-armed lever 708 cooperating by 40 rolls 709, 710 with cam disks 711, 712 rigid on the shaft 616. The pin 693 is adapted to engage the link 682 destined for driving the feeding mechanism for the control strip.

The three-armed lever 708 is rigidly fixed on 45 the shaft 701 which further has rigidly mounted on it an arm 713 (Figs. 6, 19), said arm being connected, to a link 714, by an arm 715 loosely mounted on the shaft 689 and by a link 716 pivoted to said arm 715, to the device for advancing 50 the consecutive number. The four type wheels 522, 522' (Figs. 5, 19) for the consecutive number carry on their peripheries two groups of types 0 to 9. By means of sleeves 711, 711' these type wheels are loosely mounted on the tubes 524 55 and are driven by the oscillation of both 721, 722 which are rotatable around the sleeves 711, 711'.

The bow 721 (Fig. 19) is attached to the link 716, the bow 722 is connected to the bow 721 by a longitudinal link 723. Each bow has pivoted 60 on it stepped pawls 724 engaging, in known manner, ratchet teeth 725, 725' of the type wheels, said wheels each showing two deep grooves and effecting the ratchet motion and the tens transfer of the type wheels. Spring-actuated pawls 65 728 mounted on cross beams 726, 727 further engage the ratchet teeth 725, 725', said pawls yieldingly keeping the type wheels in every position. On all the four printing places the same consecutive number is in the printing path. The 70 ratchet motion of the consecutive number does not depend, as evident, on the position of the controlling disks; this motion takes place with each operation of the machine.

The pin 694 (Fig. 20) is fixed on one arm 729 75 of a three-armed lever 730 cooperating by rolls

731 with cam disks 732, 733 rigid on the shaft 616. This pin 694 may be engaged by the link 688 destined for feeding the receipts. A bell-crank 734 is pivoted on shaft 689 (Fig. 20) and has an arm 690 connected to the link 688, said 5 bell-crank 734 being connected by two links 735, 736 to two arms 739, 740 rigid on eccentrically mounted bars 737, 738. These bars carry loose rubber drums 741, 742 which by the bell-crank 734 swinging in anti-clockwise direction, are approached to engraving drums 743, 744. These engraving drums are rigidly mounted on shafts 745, 746 mounted in the frame of the machine and carrying on their front ends toothed wheels 747, 748 (Fig. 9). The wheel 747 is in mesh with 10 a wheel 749 which in its turn, is in mesh with a toothed wheel 750.

On the driving shaft 616 (Fig. 8) are arranged a toothed segment 755 to be engaged by the wheel 750, and a locking segment 756 cooperating with 20 two pins 751 carried by the toothed wheel 750. Upon rotation of the shaft 616 the wheel 750 has imparted to it by the segment 755 a stepwise motion during which the engraving drums have imparted to them a full revolution. As long as 25 the segment 755 is not engaged by the wheel 750, this latter is locked by the locking segment 756 and the pins 751. In the position of rest the engraving drums present to the rubber drums 741, 742 (Fig. 20) a flattened portion. Between 30 this portion and the rubber drums is introduced the receipt strip which comes from a supply drum 758 mounted on a shaft 757 (Fig. 8), and is directed by a guide 759 (Figs. 8, 20). For inking the engraving drums 743, 744 there are arranged 35 ink drums 760, 761 mounted in the frame beside the first-named drums. When, upon a driving motion of the controlling slides, the link 688 (Fig. 20) is brought into engagement with the pin 694, the rubber drums 741, 742 are pressed against 40 the engraving drums 743, 744. Upon the driving motion then following, of the engraving drums by the segment 755, the receipt strip is fed by the normal length of a receipt, the front and rear side of the latter being printed at the same time 45 by the engravings.

The arm 698 attached to the link 687 (Figs. 18, 6) has pivoted to it, by means of a pin 762, a link 763 and a rack 764. The link 763 is connected to an arm 765 of a sleeve 767 (Fig. 6) 50 rotatable on a shaft 766. On the front end of this sleeve 767 is rigidly fixed a frame 768 (Figs. 6, 18) which carries a printing platen 769 extending crosswise below the type wheels arranged on the shaft 521. Upon each operation of the machine with which the link 687 is in engagement with the rocking rod 692, this printing platen is 55 pressed against the type wheels and causes the set types to be printed on the receipt.

The rack 764 is held in mesh, by a spring 770, 60 with a ratchet wheel 771 mounted on a shaft 772. This latter carries, within the range of the receipt strip, a grooved drum 773 (Fig. 20) serving for spacing the lines on the receipt strip. This line spacing drum 773 cooperates with a rubbered 65 counter arm 774 rotatably mounted in the frame of the machine. The feeding motion of the drum 773 takes place, as will be seen from the shape of the teeth of the rack 764 (Fig. 18), upon the return motion of the printing platen 769 into 70 position of rest. When this takes place, the receipt strip is pressed by the high portion of the drum 773 against the counter drum and taken along by the space of a line.

To the left-hand end of the guide for the re- 75

ceipt strip is attached the cutting device 759 (Fig. 20) for said strip. This device consists of a plate 775 (Figs. 14, 20, 9) fixed to the frame, of a counter knife 776 screwed thereto and of a 5 knife 777 (Fig. 14). The knife 777 is connected to the shaft 766 by two arms 778, said shaft having secured on its rear end an arm 779 (Figs. 14, 6) attached to the arm 690 by a link 780. When the link 683 is coupled with the rocking rod 692, 10 the knife 777 has imparted to it, simultaneously with the printing motion of the printing platen 769 (Fig. 18) a rocking motion whereby the receipt projecting to the left beyond the guide 759 is cut off and falls into a chamber 781 (Fig. 1) 15 from which it may be taken.

In order to print the card, the same is introduced, through a slot 782 (Fig. 1) provided in the front wall of the casing, between the upper portion of the type wheels arranged on the shaft 521 20 and a printing platen 783 (Fig. 16). This platen is rigidly connected by arms 784 (Figs. 16, 6) to a shaft 785 mounted in the frame, said shaft carrying at its rear end an arm 786 which is connected by a bent link 787 to the arm 690 attached to the link 684. 25

Like the card, the book is introduced through a slot 796 (Fig. 1) of the front wall of the casing between the lower part of the type wheels on shaft 520, and a printing platen 788 (Fig. 15). 30 The printing platen 788 is rigidly connected by arms 789 (Figs. 15, 6) to a shaft 790 mounted in the frame, said shaft carrying at its rear end a collar 791 supporting an arm connected by a link 792 to the arm 690 attached to the link 685. 35

Pin wheels 793, 794 (Fig. 9) serve for spacing the lines on the book and the card, said pin wheels projecting with their pins into the slots 782 and 795 (Fig. 1) and being mounted on slides 796, 797. These slides are adapted to vertically shift in guidings 798 and are pressed upwardly by springs 799. Bent-over portions 800, 805 (Figs. 1, 9) of the slides 796, 797 projecting through the casing wall serve for depressing the pin wheels 793, 794, in order to clear the slots 782, 795 upon introducing the card and book, respectively. 40

The pin wheels are rigidly connected to ratchet wheels 806 (Fig. 9) which are engaged by pawls 803, 804, acted upon by springs 807, said pawls being mounted on arms 808, 809 rotatably mounted on the axles of the pin wheels. The arm 809 has attached to it a link 810 the other end of which is connected to a double lever 812 55 pivoted on a fixed tap 811. The upper arm of this double lever is connected, by a link 813, to a link 814 which has the arm 808 pivoted to it. 50

The link 814 is connected at its right-hand end to a double lever 815 mounted on the shaft 701 (Figs. 8, 6), the lower end of this double lever being connected to a pitman 816 which is guided by its forked end on the shaft 616. By means of a roll 817 this pitman 816 engages the curved groove of a cam disk 818 (Fig. 6) rigid on the 60 driving shaft 616. Upon rotating the shaft 616 the pawls 803, 804 (Fig. 9) receive a to and fro motion by means of the links 814, 813, 810 so that the book and the card when being introduced, are fed with each operation of the machine by 65 the space of a line. 70

The arm 690 connected to the link 686 (Fig. 17) has pivoted to it a link 819 which is attached to an arm 821 rigid on a shaft 820. Another arm 823 of said shaft 820 is connected, by a 75 link 822, to a rocking frame 825 (Figs. 17, 6)

mounted on a shaft 824 and carrying the printing drum 826 for printing the control strip. This drum 826 is arranged opposite the upper part of the type wheels on the shaft 520. 5

As described hereabove, the link 682 (Fig. 13) is coupled to the pin 693 for actuating the control strip feeding device. A link 827 is attached to the left-hand end of the link 682, said link 827 being connected to a bell-crank 828 rotatable on the shaft 820, and, by means of links 829, 830, to a bell-crank 832 mounted on a shaft 831, and to a lever 834 mounted on a shaft 833. 10

The control strip 835 (Fig. 9) is fed from a supply roll 836 between cross ribs 837, 838 over a fixed guide roll 839, the printing drum 826, 15 a feeding roll 840 to the receiving roll 802 loosely mounted on the shaft 833. The supply roll 836 (Fig. 7) is mounted on a sleeve 853 connected to the hub 843 and surrounding the shaft 831. The sleeve 853 shows a slot 852 and fixes the 20 supply roll by friction in every position of rotation. The cross rib 838 is carried by two arms 841 (Figs. 7, 6) the rear of which is rigidly connected to the hub 843, projecting through the casing wall 842, of the bell-crank 832. The rib 837 is carried by arms 844 loosely mounted on the shaft 831 and so in impositive connection by a spring 845 to the rib 838 that both said ribs are pressed against one another and the control strip 835 is clamped between them. 25

The feeding roll 840 (Figs. 9, 7) is fixed on a segment 846 rigidly connected to the hub 847 of the arm 834 loosely mounted on the shaft 833. The segment 846 has further mounted on it by means of a pin 847 a clamping piece 848 showing a wedge surface 849 (Fig. 9) which is curved eccentrically relative to the pin 847. Said wedge surface cooperates with a wedge groove 850 (Fig. 7) of a disk 855 which is rigidly connected to the receiving roll 802, said wedge surface being 40 pressed into said groove by a spring 856. 30

Another clamping piece 857 (Fig. 9) engages the wedge groove 850 of the disk 855 by means of a wedge surface 854 and acted upon by a spring 858, this piece 857 being mounted by a 45 pin 859 on a segment 860 loosely arranged on the shaft 833. The segment 860 shows a recess limited by two curved surfaces 861, 862. A laterally bent lug 863 of a lever 865 loosely mounted on a fixed pin 864, projects into said recess. 50 The lever 865 is connected by a sleeve 866 (Fig. 7) to two arms 867 carrying a feeling roll 868 abutting under the action of a spring 869 (Fig. 9) against the periphery of the receiving roll. It is attained hereby that the lug 863 is at a distance away from the shaft 833 depending on the radius of the receiving roll. When a new strip is to be put on, the feeling roll 868 may be moved, 55 against the action of the spring 869, away from the receiving roll. 60

The upper surface of the control strip is situated directly under a display opening 871 (Fig. 9) of the plate 872 of the casing, through which opening the last printed lines may be read-off. The feeding device for the control strip works 65 so that in the position of rest of the machine the last line is at the place denoted by 873 (Fig. 9) where this line may be read through the display opening. Shortly before a new line is printed, this printing taking place at the point 874, the 70 last line is fed back to the point 875, where it will be one line space from the printing point. When the new line has been printed this line passes onto the place 873. These operations take place 75 in the following manner:

If the link 682 (Fig. 13) is being coupled with the pin 693, the levers 832, 834 and therewith the ribs 837, 838 (Fig. 9) and the segment 846 with the clamping piece have imparted to them a 5 rocking motion on their axis in clockwise direction. This taking place, the control strip 835 is taken along by means of said two ribs 837, 838. This causes the receiving roll 802 to turn in clockwise direction whereby the strip is paid off 10 the receiving roll a certain distance. Together with said drum 802 the grooved disk 855 will move also, taking with it by clamping action the clamping piece 857 and thus the segment 860. Now the curved surface 862 is so shaped that, in 15 the different radial positions of the feeding roll 868 it will strike the lug 863 and stop the receiving roll and the control strip when the last printed line has reached the point 875. The arms 837, 838 and the segment 846 move still 20 a little farther, the control strip 835 slipping between the ribs 837, 838. If the strip would not be stopped by the surface 862 abutting against the lug 863, the last line would reach again the place 874. When the last line has reached the 25 place 875, the printing of the new line takes place at the place denoted by 874 of the control strip. Thereupon the segment 846 and the ribs 837, 838 are swung back by the actuation of the link 682. Upon this return motion the segment 30 846 is being rigidly connected by the action of the clamping piece 848, to the receiving roll 802. As the whole forward swinging motion of the segment 846 corresponded to a feeding motion of the strip from point 873 to point 874, the strip 35 will be fed, in the return motion of the segment 846 causing the strip to be wound on the roll 802, so far that the new line travels from place 874 to place 873 where it may be seen through the display opening 871. Upon the anti-clockwise rotation of the receiving roll caused by the 40 return motion of the segment 846, also the segment 860 is taken along with by the clamping piece 857 by friction generated by the action of the spring 858, until the surface 861 of the segment 860 abuts against the lug 863. The parts 45 are now in their initial position.

The ink ribbon 876 (Fig. 20) is an endless one. It goes from an ink roll 877 serving at the same time for driving the ribbon, over a tension roll 50 878, guide rolls 879, 880 and a guide rail 881 back to the ink roll 877. It supplies both sets of type wheels.

The impression on the card (Fig. 21), the book (Fig. 22), the receipt (Figs. 23 and 24) and the 55 control strip (Fig. 25) shows, according to the different kinds of printing wheels, eight columns. The column 882 (Figs. 21, 22) comprises seven numeral positions for the consecutive number of the account, column 883 comprises four positions for the date, column 884 one position for the sign N, ZS, ES of the row of keys 12, column 60 885 shows three positions for the rows of keys 13, column 886 shows one position for the signs B to HR of the row of keys 11, column 887 comprises one position for the signs plus or minus, column 888 comprises ten positions for the amount, and column 889 shows four positions for the consecutive number counter.

Operation of the printing mechanism

70 As will be seen from the Figures 21 and 22, the card and the book of a customer will always get the same account number. The date is that of the day of the transaction. The last transaction booked on a certain day always repre-

sents a new state of account (b). The column 884 shows none of the signs ZS, ES; it will be seen therefrom that grand-totals (ES) and sub-totals (ZS) are not printed on the card and the book. The sign N in column 884 refers to 5 addenda to be made sometimes. In case the book is not present when a transaction is to be made, for instance when money is to be received on account by an order to the booking office, as it may be assumed with the transaction No. 0210 10 of 10.1.24, this transaction is recorded in the usual way on the control strip, ticket and card, but not in the book. This transaction of 10.1.24, not recorded in the book, is recorded with the next presentation of the book, for instance on 15 20.2.24 by the transaction No. 0486. The depressing of the key N causes in this case the addendum transaction to be printed in the book only and the several control totalizers to remain unacted upon. The recordings in the column 20 885 denote the account totalizers selected for the transaction by the keys 13 according to the kind of item in question. From the column 886 it is to be seen that only "received" (Zu), "paid out" (Ab) and the new state of account (b) 25 come to be recorded in the book and card; all the remaining keys of the row 11 do not influence the printing plates 788, 783 (Figs. 15, 16) for the book and the card. The sign of column 30 887 is printed with each item. Printing from the consecutive counter, column 889, takes place at every operation of the machine. When the number 9999 has been reached, a new series of numbers will begin from 0000. Only with a ticket (Fig. 23) the numbers will be consecutive, while with the book, the card and the control strip the numeral denomination is an interrupted one since not all the machine operations of a transaction are recorded thereon.

The receipt (Fig. 23) contains the complete 40 statement of a record of first order, that means the old state of account B, the amount received or paid out Zu or Ab, and the new state of the account, b. After each taking of a total, b, from the main totalizer or after taking a total (ES and ZS) from one of the controlling totalizers the receipt cutting device is operated. The long feed for printing the engraving takes place in case one of the keys B, ZS or ES has been depressed. Fig. 24 shows a receipt indicating the 45 grand-total of the control totalizer Ab.

The control strip (Fig. 25) records all the items except the old state B and the new state, b, of an ordinary transaction. The item denoted by consecutive number 0544 is a grand-total from the transaction totalizer -b. The items 0528 and 0535 denote grand-totals from the auxiliary totalizer, the items 0542 and 0543 denote sub-total and grand-total from the account totalizer 15. The item 0548 is a sub-total from the main totalizer.

The recording of the grand and sub-totals on the ticket and the control strip has the object to ascertain the state of the totalizers when the machine is to be turned over to another operator.

The different printing effects at the several printing places are attained by the shape of the controlling disks, the disks 643 to 649 (Fig. 6) being set by the keys 11 and the disks 651 to 657 being set by the keys 12.

The disks 643 and 651 (Fig. 20) serve for controlling the long feed for the receipt, with its accompanying engraving impression. The disk 643 shows a recess reaching into the range of the lug 642 of the allotted control slide when the key 75

—B or +B is being set. The disk 654 has a recess which reaches the range of the lug 641 when the key ES or ZS is being depressed. As the cross piece 640 is pivotally mounted on the controlling slide 638, the link 688 is coupled with the pin 694, in order to secure a long feed when one of the keys +B, —B, ES, ZS is set, that is, when the old state is recorded or when the total is taken from one of the control totalizers.

10 The disks 649, 651 (Fig. 14) controlling the actuation of the receipt cutting device have recesses corresponding to the keys —b, +b and ES, ZS. The cutting of the ticket therefore takes place always at the end of that operation with 15 which one of these keys is set, that is, when the new state (—b, +b) is printed or when a total is taken from one of the control totalizers.

The control of the printing platen 769 and of the line spacing mechanism for the receipt is 20 effected by the control disks 648, 656 (Fig. 18). These disks show recesses corresponding to the keys +B, —B, Zu, Ab, +b, —b and ES, ZS. Since the cross piece 640 is pivotally connected to its control slide 638 also in this case, the link 25 687 is coupled, upon setting one of said keys, with the rocking rod 692, whereby the printing of the old state, of the amounts received and paid out, of the new state, or of a total from one of the control totalizers is effected on the receipt. Upon 30 the printing platen 769 returning the rack 764 effects the line spacing in the above-described manner.

The control of the printing roll 826 (Fig. 17) for the control strip is effected by the control disks 647, 655. These disks show recesses corresponding to the keys Ab, Zu, RZ, HR and ES, ZS. The cross piece 640 is pivotally connected to its slide 638. Upon depressing one of these keys a print therefore is made of the amounts received 35 and paid out, the sub-totals of the main totalizer (RZ), and the totals from the control totalizers.

The control strip feed is controlled by the disks 644, 652 (Fig. 13). These disks show, in accordance with the disks 647, 655 (Fig. 17), recesses 40 corresponding to the keys Ab, Zu, RZ, HR and ES, ZS and effect the coupling of the link 682 (Fig. 13) with the pin 693. This latter executes its swinging motion after the printing motion of the roll 826 (Fig. 17) has been completed. The control strip is therefore fed by the space of a line 45 after each printing motion of the roll 826.

The control of the platens 788 (Fig. 15) for the book, and 783 (Fig. 16) for the card is effected by the disks 646, 654 (Fig. 15) and 645, 653 (Fig. 55 16). The disks 645, 646 present recesses corresponding to the keys Ab, Zu, —b, +b, and the disks 653, 654 allotted to the keys 12, show recesses which are, in the zero position, opposite to the lateral lugs 641. The disk 654 also has a 60 recess corresponding to the key N. The cross pieces 640 are rigid to their slides 638 so that a coupling of the rods 684, 685 can take place only if at the same time recesses of both the disks are opposite the lugs of the cross piece 640. This is 65 the case if none of the keys 12 and one of the keys Ab, Zu, —b, +b of the row 11 is depressed, or if in the row 12 the key N and in the row 11 one of the keys Ab, Zu, —b, +b is being depressed. Therefore only the received and paid out amounts 70 and the new states of account are recorded on the card and the book, and if the N key is depressed there is no recording on the card.

The line spacing device for the book and the card (Fig. 9) is operated, as described, directly 75 from the main shaft 616. A special control

mechanism for this device is not required, as the book and the card are introduced in the machine only for the duration of the printing operations intended for them.

The described arrangements of the printing 5 mechanism enable the different operations to be recorded selectively on the different record media (book, card, ticket, and control strip) in the following manner:

1. Printing the old state of account (—B, +B) 10 on the receipt only;
2. Printing the amounts received and paid out (Ab, Zu) in the book, on the card, the receipt and the control strip;
3. Printing the new state of account (+b, —b) 15 on the card, in the book and on the receipt;
4. Printing a sub-total (RZ) from the main totalizer on the control strip only;
5. Printing sub-totals and grand-totals, (ES, ZS) 20 from a control totalizer on the control strip and the receipt;
6. Printing addenda only in the book.

While the form of mechanism herein shown and described is admirably adapted to fulfil the objects primarily stated, it is to be understood that it is not intended to confine the invention to the one form of embodiment herein shown and described, as it is susceptible of embodiment in various forms, all coming within the scope of the claims which follow.

We claim:

1. In a machine of the class described, a printing mechanism comprising a plurality of sets of types adapted to print at different places, impression devices allotted to the respective sets of types, a driving mechanism for said impression devices; disengageable connections between said driving mechanism and said impression devices, whereby said impression devices are individually coupled to said driving mechanism, and a plurality of differentially movable controlling members 35 jointly cooperating with all said disengageable connections.

2. In a machine as described in claim 1, a governing mechanism comprising differentially movable actuators, said actuators being respectively connected to said controlling members for adjusting the latter.

3. A machine as described in claim 1, wherein each of said controlling members comprises a set 50 of notched controlling disks movable as a unit.

4. In a machine of the class described the combination of a printing mechanism comprising a plurality of sets of printing types adapted to print at different places, impression devices allotted to the respective sets of printing types, a driving mechanism for said printing mechanism, disengageable connections between said driving mechanism and said impression devices, two sets of notched adjustable controlling members, controlling slides connected to said disengageable connections, feeling members on said controlling slides each having two lugs whereby each feeling member cooperates with one controlling member of each set, and impositive driving means for urging said slides and feeling members against said controlling members.

5. In a machine of the class described the combination of a printing mechanism comprising a plurality of sets of printing types adapted to print 70 at different places, impression devices allotted to the respective sets of printing types, a driving mechanism for said printing mechanism, disengageable connections between said driving mechanism and said impression devices, two sets of 75

notched adjustable controlling members, controlling slides connected to said disengageable connections, feeling members rigidly mounted on said controlling slides, each having two lugs 5 whereby each feeling member cooperates with one controlling member of each set, and impositive driving means for urging said slides and feeling members against said controlling members.

6. In a machine of the class described, a printing mechanism comprising a plurality of sets of printing types adapted to print at different places, impression devices allotted to the respective sets of printing types, a rocking frame, driving means for rocking said frame for imparting a printing motion to said impression devices at each operation of the machine, and means for selectively coupling said impression devices to said rocking frame.

7. In a machine of the class described, a governing mechanism comprising differential actuators, two shafts rotatably mounted in the frame of the machine, means respectively connecting said shafts to said actuators whereby said shafts can be adjusted in different angular positions, controlling disks rigid on said shafts, controlling slides cooperating therewith, means for impositively urging said slides against said disks, a plurality of impression devices, driving means therefor, and disengageable connections between said driving means and each of said impression devices, said connections being respectively coupled to said controlling slides.

8. In a machine of the class described, a row of keys, a shaft rotatably mounted in the frame of the machine and arranged with its axis parallel to the row of keys, rigid lugs helicoidally distributed along said shaft and each cooperating with one of said keys, driving means having a motion of uniform extent, yielding connections between said driving means and shaft whereby the latter is rotated until stopped by the abutment of a lug and a key, and an indicating device connected to said shaft so as to be positioned thereby.

9. In a machine of the class described, a row of keys, a shaft rotatably mounted in the frame of the machine and arranged with its axis parallel to the row of keys, rigid lugs helicoidally distributed along said shaft and each cooperating with one of said keys, an indicating device, a rack geared to said indicating device and said shaft, driving means having a uniform extent of motion, and a yielding connection between said driving means and said rack.

10. A machine according to claim 8 in which said yielding connections comprise a pinion geared to said driving means, and means including a helical spring for coupling said pinion to said shaft.

11. In a machine according to claim 8, a stop on said shaft, and a fixed stop on the frame of the machine, both adapted to arrest said indicating device after a rotation of ten units occurring when no key is depressed.

12. In a machine of the class described, a key bank for a plurality of orders, shafts rotatably mounted in the frame of the machine and arranged with their axes respectively parallel to the rows of keys of each order, rigid lugs helicoidally distributed along said shafts and each cooperating with one of said keys, the lugs of neighboring shafts being staggered with respect to each other, driving means, yieldable connections between said driving means and all of said shafts, and

indicating devices connected to the respective shafts so as to be positioned thereby.

13. In a machine of the class described, a totalizer adapted for addition and subtraction, differential actuators for said totalizer, means for relatively adjusting said totalizer and said actuators in dependence upon the sign of an amount comprising a controlling member of unequal contour, a controlling slide, means for impositively urging said controlling slide against said controlling member, connections between said controlling slide and the member which is to be moved to determine the relative adjustment of said totalizer and said actuators, a type carrier having a plus sign and a minus sign, and connections 10 between said controlling slide and said type carrier whereby the latter is adjusted in accordance with the relative adjustment of said totalizer and said actuators.

14. In a machine of the class described, a totalizer adapted for addition and subtraction, a setting member of unequal contour having different positions corresponding to positive and negative totals of the totalizer, means controlled by said totalizer on a passage from a positive to 25 a negative total, or vice versa, for adjusting said setting member, a type carrier having a plus sign and a minus sign, a feeling member, means for yieldingly pressing said feeling member against said setting member before a printing operation 30 of said type carrier, and connections between said type carrier and said feeling member whereby the former is adjusted to a position corresponding to the position of said setting member.

15. In a machine of the class described, a printing mechanism comprising a plurality of actuating devices, a common driving mechanism for said actuating devices, disengageable connections between said driving mechanism and each of said actuating devices, a plurality of sets of 40 differentially movable controlling members, and feelers controlling the coupling of said connections, each feeler engaging controlling members of each set.

16. In a machine of the class described, a printing mechanism comprising a plurality of actuating devices, a common driving mechanism for said actuating devices, differentially movable controlling members, and disengageable connections for separately connecting said actuating devices to said driving mechanism, said connections having feelers respectively engaging said controlling members.

17. In a machine of the class described, a totalizer adapted for addition and subtraction, differential actuators for entering amounts in said totalizer, adjusting means for causing the amount to be entered positively or negatively, a type carrier having a plus sign and a minus sign, a cam driven by the driving mechanism of the 60 machine, a follower for said cam, connections between said follower and said type carrier, said cam having two alternative cam surfaces adapted to hold said type carrier through the intermediary of said connections in either plus sign 65 or minus sign printing position during the printing operation, and means controlled by said adjusting means for shifting said follower from one cam surface to the other.

18. In a machine of the class described, a totalizer adapted for addition and subtraction, differential actuators for entering amounts in said totalizer, adjusting means for causing the amount to be entered positively or negatively, a type carrier having a plus sign and a minus sign, 75

a cam driven by the driving mechanism of the machine, a follower for said cam, connections between said follower and said type carrier, said follower being normally disengaged from said cam and said type carrier being normally in one of its two printing positions, and means controlled by said adjusting means for moving said follower into engagement with said cam, whereby said type carrier is moved and held during the printing operation in the other of its printing positions.

19. In a machine according to claim 1, notches in said controlling members, controlling slides connected to said disengageable connections and 15 cooperating with said controlling members, driving members having a uniform extent of motion, and impositive connections between the latter members and said controlling slides.

20. A machine according to claim 1, in which said disengageable connections comprise rods pivoted at one end to one of the parts to be connected and having slots at their other ends adapted to be brought into and out of engagement with the other of said parts to be connected, controlling slides movable at right angles to said rods and connected therewith, said slides cooperating with said controlling members, pins on said slides engaging said slots, and impositive 10 connections between said slides and said driving mechanism.

CERTIFICATE OF CORRECTION.

Patent No. 2,070,419.

February 9, 1937.

MARTHA BORNKESSEL, ADMINISTRATRIX OF BRUNO BORNKESSEL, DECEASED, ET. AL.

It is hereby certified that error appears in the printed specification of the above numbered patent requiring correction as follows: Page 2, first column, line 28, for the words "total-making including" read total-taking included; page 4, second column, line 72, for the numeral "21" read 221; page 8, first column, line 58, after the word "unit" insert upon; page 9, first column, line 50, for "(Fig. 32)" read (Fig. 33); and second column, line 25, after "embracing" insert the comma and word , by; page 11, first column, line 27, for "796" read 795; line 67, for "913" read 813; and second column, line 57, for "slip" read roll; page 13, first column, line 45, after "corresponding" insert to; and that the said Letters Patent should be read with these corrections therein that the same may conform to the record of the case in the Patent Office.

Signed and sealed this 30th day of March, A. D. 1937.

Henry Van Arsdale
Acting Commissioner of Patents.

5 a cam driven by the driving mechanism of the machine, a follower for said cam, connections between said follower and said type carrier, said follower being normally disengaged from said cam and said type carrier being normally in one of its two printing positions, and means controlled by said adjusting means for moving said follower into engagement with said cam, whereby said type carrier is moved and held during the 10 printing operation in the other of its printing positions.

15 19. In a machine according to claim 1, notches in said controlling members, controlling slides connected to said disengageable connections and 15 cooperating with said controlling members, driving members having a uniform extent of motion, and impositive connections between the latter members and said controlling slides.

20. A machine according to claim 1, in which said disengageable connections comprise rods pivoted at one end to one of the parts to be connected and having slots at their other ends adapted to be brought into and out of engagement with the other of said parts to be connected, controlling slides movable at right angles to said rods and connected therewith, said slides cooperating with said controlling members, pins on said slides engaging said slots, and impositive 10 connections between said slides and said driving mechanism. 5
